Joseph Cuomo, 25 Queen Ave., Methuen, Mass.

Filed May 18, 1965, Ser. No. 85,332

Term of patent 3½ years

(Cl. D72—1)

Fig. 1.

Fig. 2.

Fig. 3.

Fig. 4.

FIGURE 1 is a perspective view taken from the top, front and one side of a fire alarm cabinet showing my new design;

FIGURE 2 is an elevational view thereof taken from the side opposite that shown in FIG. 1;

FIGURE 3 is a rear elevational view thereof; and

FIGURE 4 is a bottom plan view thereof.

It is understood that the apertures shown fragmentarily in FIGS. 1, 2 and 3 are continuous throughout the area in which they are shown.

I claim:

The ornamental design for a fire alarm cabinet or similar article, substantially as shown and described.
